METHOD AND MEANS OF PERFORATING
PIPE

Arthur L. Armentrout, Los Angeles, Calif.

Application September 26, 1940, Serial No. 255,972

13 Claims. (Cl. 164—9.2)

This invention relates to oil field equipment and particularly pertains to a method and means of perforating pipe.

In connection with the development of oil wells and the like and in placing them on production it is common practice to utilize a perforated string of pipe or screen casing through which the cognate fluid from the formation may flow and after which the fluid may be elevated to the surface. In some instances the perforated pipe or casing is perforated above ground and thereafter lowered into the hole. These perforations are usually undercut so that the opening of the perforations will be larger on the inside of the casing than it is on the outside of the casing. Due to this arrangement silt and other material is screened out of the perforations, and the perforations are furthermore kept clear since the restricted orifice at the outer surface of the casing wall increases the velocity of the fluid flowing through the perforation. In certain wells the producing horizon is not ascertained while casing is being set and it is necessary, therefore, to provide some means for perforating the casing after it is in place. Various mechanical devices have been provided for this purpose which punch or cut holes through the wall of the casing. Perforating guns have also been provided for forcing a projectile through the wall of the casing and other means, such as abrasive fluid jets, have been used in perforating the casing walls. It is the principle object of the present invention to provide efficient means whereby the perforations may be rapidly cut electrically by creating an arc at a desired point of perforation and gradually forcing an electrode against and through the casing wall while the erosive action of the arc forms a perforation of a substantially uniform size and which perforation has the characteristic of having a larger opening along the inner surface of the wall than it does at the outer surface, thereby producing a desirable undercut perforation.

The present invention contemplates the provision of a tool which can be mounted on a suitable suspending member and lowered into a well bore, and which may be thereafter manipulated to create an electric current and project an electrode against the wall of the casing to form a perforation therethrough, the structure also lending itself to an operation whereby the lengths of casing may be perforated above ground.

The invention is illustrated by way of example in the accompanying drawings, in which:

Figure 1 is a view showing the perforating gun supported from a drill string.

Fig. 2 is an enlarged view in longitudinal section showing the upper end of the perforating gun and indicating the trip mechanism actuated from the top of the well.

Fig. 3 is an enlarged view in central section showing the operating solenoid and the valve element associated therewith.

10 Fig. 4 is a fragmentary view in longitudinal section showing the plunger structure.

Fig. 5 is a view in fragmentary section showing the means for ejecting the perforating electrode from the casing.

15 Fig. 6 is an enlarged fragmentary view showing a part of the structure disclosed in Fig. 5, indicating the ejecting members in elevation.

Fig. 7 is a view in transverse section through the ejecting structure as seen on the line 7—7 of Fig. 6.

20 Fig. 8 is a view in longitudinal section disclosing the operating parts of the present invention in diagram and indicating the electric circuits and the manner in which the various moving parts function.

Fig. 9 is a view similar to Fig. 6, showing the electrodes moved to their outermost positions and indicating the action of the operating wedges.

Referring more particularly to the drawings, 30 10 indicates a string of drill pipe at the lower end of which is mounted a sub 11. The sub 11 has a threaded pin 12 at its lower end to receive a tubular battery casing 13 which is threaded thereover. At the lower end of the battery case

35 13 is a solenoid valve housing 14 which is provided with an upper threaded portion 15 extending into the housing 13. The lower end of the solenoid valve housing 14 is internally threaded and receives the threaded end 16 of a valve chamber housing 17. The lower end of the valve chamber housing is fitted with a threaded pin 18 extending into the threaded bore of a valve plunger housing 19. The valve plunger housing 19 is internally threaded at its lower end and receives a pin 20 of the electrode housing 21. The lower end of this housing is fitted with a threaded pin 22 extending into the threaded bore of an expanding cone element 23 which carries an expanding cone 24 along which gripping slips 25 may move. The gripping slips 25 are supported on spring arms 26 carried upon the frame of a spring basket 27 having springs 28 which frictionally engage the wall of a casing 29 into which the entire structure is lowered, and which casing is to be perforated. It is to be un-

derstood that all of the various sleeves and housings previously described are assembled together and that they form the complete enclosure for the perforating structure with which the present invention is concerned.

Briefly considered, the principal operation of this invention is to provide electrodes which are projected outwardly into contact with a circumscribing piece of pipe and which electrodes are moved gradually by the action of a solenoid, the movement of which is hydraulically controlled and checked so that the electrode will be fed slowly outwardly from the body of the housing and to a contacting and perforating position with relation to the casing.

Referring particularly to Fig. 2, it will be seen that the upper pin end 38 of the sub 11 is internally threaded to receive a bushing 31. The bushing 31 is formed with a counterbore 32 which terminates in a central bore 33. Reciprocating through the counterbore and the central bore 33 is a trip pin 34. This pin is formed at its upper end with an enlarged head 35 which is presented to the opposite lower end of the central bore 33 of the tubular supporting element 10. The lower end of the pin is threaded, as indicated at 37, and projects below the lower end of the bushing 31 and into a sleeve 38. The threaded end of the pin 34 engages the bore of a contact plunger 39. This plunger is made of dielectric material and supports a metal contact ring 40 adjacent to its end and when moved downwardly will engage spring contact fingers 41 and 42 which are included within an electric circuit to be hereinafter described. The spring contact fingers are formed as a part of a tubular member fitting within the lower end of the sleeve 38 and being held downwardly by engagement of the end of the sleeve with a flange 43. The flange 43 rests against an insulating washer 44 which occurs at the bottom of the bore 45 within which the sleeve 38 is seated.

The pin 34 is designed to be forced to its lower position by the dropping of an instrument through the pipe 10. These instruments are designated in the trade as go-devils (24'), and are heavy bars of metal of sufficient weight to force the pin 34 downwardly when the bar strikes the head 35. In order to hold the pin in its innermost position after it has been thus struck a spring bushing 46 is provided having spring fingers 47 which extend inwardly around the shoulder on the head when the pin is in its uppermost position, and which flex over the end of the pin when the pin is in its lowermost position, whereby the pin will be locked in its lowermost position. The purpose of this pin is to insure that electric circuits to be completed within the apparatus are not completed until the operator so desires, thus avoiding accidental operation of the tool.

As a continuation of the bore 45 within the sub 11 is a central restricted circulation bore 48 which extends downwardly to communicate with the compartment within the battery casing 13. An insulation washer 49 is disposed at the lower end of the pin 12 of the sub 11 and lies over the top of a series of batteries 50 which furnish electrical energy for the solenoid as well as electrical energy for the electrode.

Referring particularly to Fig. 3 of the drawings, it will be seen that the solenoid valve housing 14 is formed at its upper end with a central bore 51. This bore is formed with a threaded counterbore 52 at its upper end into which a

solenoid unit 53 is secured. This solenoid unit comprises a central spool-shaped core 54 around which a magnetic coil 55 is arranged. Disposed between the coil and the side of the bore is an insulating covering 56. The core 54 has a central cylindrical bore 57 through it and within which bore a solenoid pin 58 reciprocates. The pin extends downwardly below the core 54 and terminates in a conical point 59 at its end. A collar 61 is formed on the pin to limit the upward movement of the pin into the core of the solenoid. The downwardly extending portion of the pin passes into a sleeve 62 which has a partition wall 63 at a point intermediate its length. Resting upon this partition wall and exerting a force against the collar 61 is a spring 64 which tends to hold the pin upwardly against the action of the solenoid. The sleeve 62 rests against a shoulder 65 at the lower end of the bore 66 within which the sleeve 62 fits. A reduced bore 67 extends downwardly within the valve chamber housing 17 from the bore 66. Mounted within this reduced bore is a tubular plunger 68. This plunger is formed at its upper end with a threaded counterbore 69 which receives a threaded ring 70. The counterbore forms a shoulder adjacent to the upper end of a central passageway 71. The threaded ring 70 holds a breakable disc 72 over the end of the bore 71 and when the conical point 59 of the pin 58 moves downwardly it will penetrate and break the disc 72 so that an opening will be effected to the bore 71. Mounted in the lower end of the tubular plunger 68 is a tubular extension 73. This extension is threaded into the end of the plunger 68 and carries packing members 74 which create a tight sliding fit with the bore of a cylinder 75. A circulation passageway 76 extends downwardly into the tubular extension to a point below the packing member 74 and is provided with lateral outlet openings 77 which communicate with the cylinder 75. A cylinder plug 78 is threaded into the lower end of the member 75 and forms a packing for the lower end of the extension member 73. Formed in the wall of the plug 78 are restricted orifice bushings 79 which control the outlet of fluid from the cylinder 75 and cause the cylinder to have a dash-pot action to control the movement of the plunger for a purpose to be hereinafter described.

The lower end of the plug 78 is internally threaded to receive a coupling 80. An extension of this coupling is threaded to receive a tube 81 within which a spring 82 is positioned. The upper end of the spring 82 rests against the lower end of the coupling. The lower end of the spring 82 rests against the head 83 of a plunger 84. The plunger 84 extends downwardly through a cap 85 carried at the lower end of the tube 81. Carried upon the tube 81 near its lower end is a piston member 86 which has a sliding fit with the internal bore 87 of the valve plunger housing 19. The lower end of the plunger 84 is conical as indicated at 88 and has a rounded point which projects through an opening 89 in the upper end of the electrode housing 21 and rests upon an arcuate member 90 formed at the upper end of the electrode wedge 91. The electrode wedge is formed with an inclined face 92 and a straight back face 93. As shown in Fig. 6 of the drawings, pairs of these wedges 91 are assembled with their inclined faces 92 disposed in opposite directions for separately actuating electrodes 94 which may be projected oppositely from the body of the housing 21. The electrodes 94 are

disposed in a plane at right angles to the longitudinal axis of the housing 21 and project through packings 95 mounted in bores 86 in the side wall of the housing and secured by threaded nuts 97. As shown in Fig. 5 of the drawings, a shoulder 98 is formed on each of the wedges and rests against a spring 99. The spring 99 is disposed around a rod 100. The springs act to hold the wedges 91 in their retracted position. The electrodes are supported by springs 101 which tend to hold the electrodes in their retracted positions. Disposed beneath the electrode housing is the expanding core element 23 which is associated with a spring basket acting to frictionally engage the side wall of the casing 28 so that when the perforated tool is in any desired set position the spring basket will tend to center the tool in the middle of the casing and insure that the electrodes will contact the casing with substantially equal pressure as the perforating operation proceeds.

In operation of the present invention the device is assembled as here shown. The spring contact fingers 41 and 42 are connected with conductors 102 and 103. A fuse 104 is placed in the line of the conductor 102. This conductor leads to one pole of the solenoid coil 53. The opposite pole of the solenoid coil 53 is connected by a conductor 103 to one of the batteries 50. The opposite pole of this particular battery connects with the conductor 103. The batteries are in series. A wire 104 connects the positive with the negative of the batteries and a wire 105 connects the battery with the member 73, which in turn is provided with a wire 106 establishing connection with the electrodes 94. Attention is also called to the fact that the conductor 103 is grounded to the housing 13 so that a circuit will be completed between the casing 28 and the electrode 94 when the electrode is pushed outwardly from the body and into contact with the casing. It is to be understood that the various circuits are protected by suitable insulation so that there will not be any short circuits before the electrode actually contacts the casing.

When the structure is wired and assembled as shown in the drawings, it is then lowered into the hole. At the selected point for making perforations the spring basket is manipulated so that it will seat and allow the slips 25 to move outwardly and engage the wall of the hole to hold the structure tightly and to prevent it from moving longitudinally. The go-devil is then dropped through the string of pipe 18 so that it will strike the head 35 of the pin 34. This will force the pin 34 downwardly against the action of the spring 107 until the head of the spring moves beneath the spring fingers 41. These fingers will then lock the head in its innermost position and will hold the contact ring 40 downwardly in a position of contact between the fingers 41 and 42. This will complete two circuits through the batteries 50. It will be understood that as many batteries may be provided as necessary for producing the desired electric current, although only two are shown in the drawings. After the go-devil has been dropped to move the pin 34 downwardly one circuit established will energize the solenoid coil 53. When this coil is energized it will move the pin 58 downwardly against the expansive action of spring 84. It will be understood that the spring 84 has been acting to hold the pin 58 in its uppermost position. When the pin 58 moves downwardly its conical point 66 will enter the open-

ing in the ring 61 and break the diaphragm 72. When this takes places the circulating fluid will force its way downwardly through the tubular plunger 68 moving it downwardly against the expansion of spring 82, which will in turn force the plunger 84 downwardly. This movement is resisted and controlled by the escape of fluid from the restricted opening 78 in the plug 78 as the packing members 74 move downwardly, the result being that the action of the electrode is retarded so the extension member 73 is gradually forced downwardly as the fluid from the cylinder 15 is exhausted. As the member 84 moves downwardly it exerts a pressure upon the wedge members 91. This forces the inclined wedge faces 82 against the inner ends of the electrodes 94 and gradually forces the electrodes out and into contact with the casing 28. Attention is directed to the fact that a spring 82 is interposed between the extension member 73 and the rod 84 so that the electrode will not be forced outwardly by a positive mechanical action but in a manner to yieldably force the electrode against the casing as it contacts therewith and creates an arc which will burn a hole in the casing. Attention is directed to the fact that the arc will form a crater on the contacting side of the casing so that the perforation produced will be undercut and will be of larger diameter within the casing than it is on the outside.

By reference to Fig. 9 of the drawings the action of the electrode in perforating the casing is indicated. The duration of the electric circuit is controlled by the time fuse 104. This fuse has been selected so that the electrode will have had sufficient time to burn a hole through the casing before the current flow is interrupted. By the time the hole has been burned through the casing it may be that the point of the electrode or a portion of its length will be burned away. It will not be difficult, therefore, to withdraw the entire tool from the well without any retarding action from the electrode. In the event that the electrode is not burned away it may be broken off. It is to be understood that while two electrodes are shown that any number of electrodes may be provided and operated simultaneously.

It will thus be seen that the method and means of perforating a casing here disclosed insures that a casing may be perforated with a uniform undercut hole with certainty of action and without possibility of splitting the casing as is now often done, and by means that are direct in operation and easily controlled.

While I have shown the preferred method of performing my invention and a preferred apparatus for use in practising the same, it is to be understood that various changes might be made in the steps of the method and the combination of parts of the apparatus by those skilled in the art without departing from the spirit of the invention as shown.

Having thus described my invention, what I claim and desire to secure by Letters Patent is:

1. A method of perforating a well casing which consists in positioning an electrode into a well casing to a desired point of perforation, thereafter bringing the electrode into contact with the wall of the casing to be perforated, and then establishing an electric circuit, causing an arc to be created at the point of the electrode whereby a perforation will be burned through the wall of the casing.

2. A well casing perforating device comprising a body member adapted to be positioned within a well casing, an electrode carried thereby, means for moving the electrode into contact with the well casing, an electric circuit for the electrode, and means for controlling the same whereby the electrode will burn a perforation through the casing.

3. A device as in claim 2, said controlling means including a timing element to control the duration of current flow.

4. A device for perforating well casing and the like which comprises a perforating unit adapted to be positioned at a desired point within a well casing, a source of electricity included within the unit, an electrode carried by the unit and adapted to move laterally to a point in contact with a casing to be perforated, means for moving the same, and control means, the action of which is manipulated from a point remote from the unit to initiate actuation of the electrode and to establish an electric current therethrough.

5. A device as in claim 4 and means interrupting the electric current after a predetermined time.

6. A device for perforating well casing and the like which comprises a perforating unit adapted to be positioned at a desired point within a well casing, a source of electricity included within the unit, an electrode carried by the unit and adapted to move laterally to a point in contact with a casing to be perforated, means for moving the same, control means, the action of which is manipulated from a point remote from the unit to initiate actuation of the electrode and to establish an electric current therethrough, and means acting to center the unit within the casing.

7. A perforating device adapted to be lowered into a well casing to form perforations in the same, including a string of pipe, a perforating unit suspended at the lower end thereof, said unit including an outer housing, electrodes laterally movable with relation to the housing to contact the wall of a casing to be perforated, a source of electrical energy within the housing to supply electric current to the electrodes, means for gradually feeding the electrode outwardly in a perforating operation, and means actuated by the dropping of a go-devil through the drill string for initiating operation of said feed means and establishing said circuit.

8. A device as in claim 7 and means acting to interrupt said circuit at the conclusion of a perforating operation.

9. A perforating device adapted to be lowered into a well casing to form perforations in the same, including a string of pipe, a perforating unit suspended at the lower end thereof, said unit including an outer housing, electrodes laterally movable with relation to the housing to

contact the walls of a casing to be perforated, a source of electrical energy within the housing to supply electric current to the electrodes, means for gradually feeding the electrode outwardly in a perforating operation, means actuated by the dropping of a go-devil through the drill string for initiating operation of said feed means and establishing said circuit, and yieldable means disposed between the electrode and its operating means whereby the electrode will be yieldably fed against the casing.

10. A perforating device adapted to be lowered into a well casing to form perforations in the same, including a string of pipe, a perforating unit suspended at the lower end thereof, said unit including an outer housing, electrodes laterally movable with relation to the housing to contact the wall of a casing to be perforated, a source of electrical energy within the housing to supply electric current to the electrodes, means for gradually feeding the electrode outwardly in a perforating operation, means actuated by the dropping of a go-devil through the drill string for initiating operation of said feed means and establishing said circuit, means acting to interrupt said circuit at the conclusion of a perforating operation, and means for disposing the perforating unit centrally of the casing and locking the same preparatory to the perforating operation.

11. A device for perforating well casing and the like comprising a string of pipe adapted to be lowered into a well, a perforating unit at the lower end thereof, said unit including a housing, laterally movable electrodes carried thereby, a solenoid within the housing having a plunger moving to initiate an electrode feeding action, and means between said plunger and the electrodes for transmitting motion of the plunger to the electrodes.

12. A device as in claim 11, said last named means including a dash-pot acting to retard the plunger of the electrode and the resulting movement of the electrode.

13. A device for perforating well casing and the like comprising a string of pipe adapted to be lowered into a well, a perforating unit at the lower end thereof, said unit including a housing, laterally movable electrodes carried thereby, a solenoid within the housing having a plunger moving to initiate an electrode feeding action, means between said plunger and the electrodes for transmitting motion of the plunger to the electrodes, said last named means including a dash-pot acting to retard the plunger of the electrodes and the resulting movement of the electrodes, and yieldable means interposed at a point between the plunger of the solenoid and the electrodes and through which the moving force of the plunger is transmitted to the electrodes.

ARTHUR L. ARMENTROUT.
